UNITED STATES PATENT OFFICE.

ALFRED W. BJORNSTAD, OF ST. PAUL, MINNESOTA.

RELIEF MAP.

Application filed February 23, 1921. Serial No. 447,263.

To all whom it may concern:

Be it known that I, ALFRED W. BJORNSTAD, a citizen of the United States, residing at St. Paul, in the county of Ramsey and 5 State of Minnesota, have invented a new and useful Improvement in Relief Maps, of which the following is a specification.

My invention relates to relief maps and particularly to the type of map formed with 10 a number of sections adapted to be placed adjoining each other to make a complete map and has for its object to provide a construction which will conform to the contour of the land which the map represents and 15 which will be light in weight having sufficient strength and rigidity to form a substantial structure.

Another object of the invention is to provide a solid back with a cushion member 20 mounted thereon for the reception of tacks or pins used in conjunction with the map.

In carrying out the objects of my invention I provide one or more map sections, each comprising a metal back pressed into 25 the desired shape to conform to the contour of the land represented by the map and bound with a metal edge. On this metallic backing is mounted a penetrable cushion member being pressed out to fit the back 30 member over its entire surface.

The full objects and advantages of my invention will appear in connection with the detailed description thereof and are particularly pointed out in the claims.

35 In the drawings, forming a part of this specification:

Fig. 1 is a plan view of a portion of a map embodying my invention.

Fig. 2 is a section on line 2—2 of Fig. 1.

40 Fig. 3 is an enlarged sectional detail view of a corner of the device shown in Fig. 2.

Fig. 4 is a bottom view of the parts shown in Fig. 3.

45 Fig. 5 is a view similar to Fig. 3 showing a modification of the invention.

In the ordinary type of relief map the surface of the map which is usually very 50 irregular depending upon the contour of the land which is represented by the map, is secured by casting a solid base of plaster of Paris or some other suitable plastic material in a mold previously constructed to conform to the contour of the map. On this 55 plaster of Paris base is formed a map which may be made by painting directly on the base or by cementing on paper or other body

member having the map printed thereon. This makes an exceedingly heavy construction which is very breakable.

In my invention, as indicated in Fig. 1, I 60 have shown a number of map sections 10, 11, 12 and 13 placed adjacent each other to form a portion of a complete relief map. Each of the sections 10, 11, 12 and 13 comprises a rigid back 14 which is formed to 65 correspond to the contour of the land represented and extends completely across the section, being bound on its edges by a band 15 extending completely around the same.

The exact construction of the back 14 can 70 best be seen in Fig. 3. A metal backing 16 is first formed by pressing a thin sheet of metal between suitable dies to give the required shape to the same, which back is 75 preferably soldered to bands 15 which may be also constructed of metal. Bands 15 are cut to fit the cross section of the map at the intersections of the various sections 10, 11, 12 and 13, so that the metal back 16 and the band 15 which are soldered together form a 80 sharp corner at 17.

In addition to back 16 I provide a penetrable body member 18 which has glued to it a surface member 19 both of which are simultaneously placed together in dies similar to those used in forming the back 16. Cushion member 18 may be formed of a substance having as a body some form of paper pulp or other suitable material which can be readily bent or pressed into the desired shape without breaking or tearing to 90 pieces. The surface member 19 is preferably formed of a tough paper which is capable of being stretched and compressed 95 in the dies.

After body 18 and the surface member 19 have been properly shaped the same are cemented to the metallic back 16 with any suitable cement or adhesive. The surface member 19 has printed on it all of the data desired to be shown on the map including mountains, rivers, towns, railroads and section lines, and such other data as is desired to show on the map, making the same appear as indicated at 20 in Figure 1.

For making a rigid structure of each map section the band 15 which extends around the edges of said map section and is soldered thereto, is formed at its bottom with a flange 21 whose edge is rolled over at 22, as 110 is clearly indicated in Fig. 3. These flanges 21 have their corners mitered and soldered

together at 23 thus making the entire device one complete rigid structure.

Although a comparatively thin sheet of metal may be used for the metal back 16 of the device, when this sheet of metal lies flat the same is more or less flimsy and is easily distorted out of its normal form. When, however, the same has been pressed into the form indicated in Fig. 2 said back no longer lies in a plane surface but comprises curves and bends which extend in various directions and have an arch effect upon the structure and make the entire back extremely rigid. Any flexure of the structure is completely prevented when the bands 15 are soldered to said metal back 16 so that in its entirety every map section is fully as rigid as the former type of construction embodying the plaster cast.

In Fig. 5 is shown a modification of the invention. This form is similar to that shown in Figs. 3 and 4 in having the metal back bound together at its edges with the band 15. The body member mounted on this back, however, may be constructed of a single sheet of some elastic material such as rubber or some rubber composition indicated at 24. The surface of this material has directly printed on it, as indicated at 25, the map features which in the other form of the invention are printed on the surface member 19. The body portion 24 is also cemented to the metal back 16.

In using the map it is often desirous to insert small pins or tacks 26 in the map to refer to particular locations on the map. With either form of my invention this may readily be done by simply pressing the pins or tacks 26 into the cushion member 18 or the body member 24 of the two forms of the invention as clearly indicated. When a paper pulp or similar form of cushion member is used such as indicated at 18 the gripping effect of said cushion member on the tack is sufficient so that the tack does not have to penetrate deeply into the said cushion member to hold the same in place. It hence becomes obvious that cushion member 18 does not necessarily have to be very thick. In the form of the invention shown in Fig. 5 in which a rubber composition is used for the body portion 24 the tack holes completely close up when the tack is removed so that the punctures remain absolutely invisible and the surface of the map is not marred.

The advantages of my invention are manifest. The map sections can be constructed much cheaper than the plaster of Paris casts. The sections are light in weight and have sufficient rigidity to properly hold the surface of the device in the desired form. Breakage of the sections of the map is absolutely eliminated, and the handling and manipulation of the sections in the use of

the map is clearly expedited. With binding bands soldered to the metal back a sharp corner may be secured on each of the sections, which when placed together adjacent each other provide a smooth surface on the map across the joints of the sections thus preserving the continuity of the map.

With a plaster of Paris cast the corners have to be rounded off to prevent chipping which has the effect of breaking up the continuity of the surface of the map. This is clearly eliminated in my invention.

In accordance with the patent statutes I have described the principles of operation of my invention, together with the apparatus which I now consider to represent the best embodiment thereof, but I desire to have it understood that the construction shown is only illustrative and that the invention can be carried out by other means and applied to uses other than those above set forth within the scope of the following claims.

I claim:

1. A relief map comprising a metal back having its surface pressed out to conform to the contour of the land represented by the map, a cushion member mounted on said back, covering its entire surface and a surface member mounted on said cushion member having printed on it a map, said cushion member conforming to the surface of the back throughout its entire surface, a metal band extending around the edge of said metal back and soldered thereto and a flange formed on said band extending inwardly from the edge thereof, said flange having an inwardly turned edge.

2. A relief map comprising a metal back having its surface pressed out to conform to the contour of the land represented by the map, and a body member formed by gluing together a penetrable cushion member and a surface member having a map printed thereon, said body being pressed to conform to the surface of said back and cemented thereto.

3. A relief map comprising a metal back having its surface pressed to conform to the contour of the land represented by the map, a cushion member mounted on said back covering its entire surface and a surface member mounted on said cushion member having printed on it a map, said cushion and surface members conforming to the surface of the back throughout its entire surface.

4. A relief map comprising a rigid back of uniform thickness and irregular contour, a cushion member completely covering said back and a map secured to said cushion member, said cushion and map conforming in contour to said back.

5. A relief map comprising a metal back having its surface pressed out to conform to the contour of the land represented by the

- map, a metal band extending around the edge of said metal back having an edge conforming in contour to the cross section of the map at the edge thereof, said band being 5 soldered to the back along said edge, a flange formed on said band issuing therefrom at right angles for forming a base for said back and an inwardly turned edge formed on said base for giving said base a rounded 10 edge.
6. A relief map comprising a rigid back of uniform thickness, a penetrable cushion member secured to said back and a map secured to said cushion member.
- 15 7. A relief map comprising a rigid back of uniform thickness throughout, of irregular contour, a penetrable body member secured to said back and a map mounted on
- said penetrable body member, said penetrable body and map conforming in contour 20 to said back.
8. A relief map comprising a rigid back of uniform thickness throughout of irregular contour, a band extending around the edges of said back and secured thereto and 25 an inwardly extending flange formed on said band.
9. A relief map comprising a metal back of irregular contour, a body member consisting of a penetrable material of a thickness 30 in excess of the thickness of said back, adapted to receive and hold a number of said piercing members and a map secured to said body member, said body and map conforming in contour to said back.

ALFRED W. BJORNSTAD.
